UNITED STATES PATENT OFFICE.

CHARLES E. GUENTHER, OF KNOWLTON, AND PETER MURRAY, OF WAUSAU, WISCONSIN.

DESIGN FOR A SAW-BLADE.

SPECIFICATION forming part of Design No. 31,155, dated July 4, 1899.

Application filed June 6, 1899. Serial No. 719,610. Term of patent 14 years.

To all whom it may concern:

Be it known that we, CHARLES E. GUENTHER, residing at the village of Knowlton, and PETER MURRAY, residing at the city of Wausau, in the county of Marathon, State of Wisconsin, citizens of the United States, have invented and produced a new and original Design for a Saw-Blade; and we do hereby declare the following to be a full, clear, and exact description of the invention, such as will enable others skilled in the to which it appertains to make and use the same.

Our invention relates to a new design for a saw-blade; and the design consists, essentially, of a saw-blade having teeth of the general form of the capital letter "Y" alternating with groups of straight single-pointed teeth, the base portion of the Y-shaped teeth being wider than the straight teeth, and the points of each of said Y-shaped teeth diverging at an angle of approximately ninety degrees to each other and being narrower than the straight teeth, their sides being straight and their ends having a single bevel, as seen in the accompanying drawing.

In the accompanying drawing, which represents a side elevation of our design, 1 designates the Y-shaped teeth, having relatively wide base portion 2 and relatively narrow diverging points 3 and beveled ends 4, and 5 designates the straight teeth, arranged in symmetrical groups of four and having double-beveled points 6. The teeth 5 are spaced at equal distances apart; but the distance between the base portions of the teeth 1 and the adjacent teeth 5 is several times greater than the distance between the teeth 5, and the bases of the teeth are connected by curved lines.

What we claim is--

The design for a saw-blade, substantially as herein shown and described.

In testimony whereof we affix our signatures in presence of two witnesses.

CHARLES E. GUENTHER.
PETER MURRAY.
